(57) **CLAIM**

We claim ornamental design for a syringe holder, as shown and described.

DESCRIPTION

FIG. 1 is a front elevational view of a syringe holder and a sampling arm of a sample receiving assembly, with the syringe holder shown attached to the sampling arm.

FIG. 2 is a rear elevational view thereof.

FIG. 3 is a top plan view thereof.

FIG. 4 is a bottom plan view thereof.

FIG. 5 is a right side elevational view thereof.

FIG. 6 is a left side elevational view thereof.

FIG. 7 is a perspective view thereof.

FIG. 8 is a right side elevational view of the syringe holder and the sampling arm, with the sampling arm shown attached to a sample receiving assembly, with a syringe shown positioned in the syringe holder, and with the syringe holder shown in a locked position; and,

FIG. 9 is a right side elevational view of the syringe holder and the sampling arm, with the sampling arm shown attached to the sample receiving assembly, with the syringe shown positioned in the syringe holder, and with the syringe holder shown in an unlocked position.

The broken lines depict portions of the syringe holder and the sampling arm of a sample receiving assembly that form no part of the claimed design; the broken lines and the unshaded surfaces form no part of the claimed design.

1 Claim, 7 Drawing Sheets
